US00D942036S

(12) **United States Design Patent** (10) **Patent No.:** **US D942,036 S**
(45) **Date of Patent:** **** Jan. 25, 2022**

(54) **SCOPE WARMER APPARATUS**

(71) Applicant: **Steve Eubanks**, Winter Park, FL (US)

(72) Inventor: **Steve Eubanks**, Winter Park, FL (US)

(73) Assignee: **Steve Eubanks**, Winter Park, FL (US)

(**) Term: **15 Years**

(21) Appl. No.: **29/747,610**

(22) Filed: **Aug. 24, 2020**

Related U.S. Application Data

(63) Continuation of application No. 29/712,686, filed on Nov. 11, 2019, now Pat. No. Des. 894,425, which is a continuation of application No. 29/617,851, filed on Sep. 15, 2017, now Pat. No. Des. 868,997.

(57) **CLAIM**

The ornamental design for a scope warmer apparatus, as shown and described.

DESCRIPTION

FIG. 1 is a perspective view of a scope warmer apparatus;

FIG. 2 is a front end view thereof;

FIG. 3 is a back end view thereof;

FIG. 4 is a left side view thereof;

FIG. 5 is a right side view thereof;

FIG. 6 is a top view thereof; and,

FIG. 7 is a bottom view thereof.

The broken lines depict portions of the scope warmer apparatus that form no part of the claimed design.

1 Claim, 7 Drawing Sheets
